PORTABLE FOOT SPRAYING APPARATUS

Frederick B. Eilers, Rochester, N. Y.

Application April 19, 1938, Serial No. 202,924

3 Claims. (Cl. 128—173)

This invention relates to a portable foot spraying apparatus, and has for its purpose to afford a simple construction that can be economically manufactured, to be used in connection with swimming pools, gymnasiums, and shower rooms, for conveniently and readily applying an antiseptic or cleansing liquid to the feet in a clean and thoroughly sanitary manner.

Heretofore, the practice has been to place a solution in a shallow pan, and immerse the foot in the liquid, even though the latter has become dirty from continued use, and it is a purpose of this invention to overcome the disadvantages of such a procedure by providing a foot receptacle 10 separate from a liquid container, but combined in one portable unit, and spraying the liquid on to the foot while the latter is supported above the bottom of the receptacle so that each user has a fresh application of the solution and there 20 is no necessity of immersing the foot in the solution.

An additional object of the invention is to afford a practical structure involving a suitable foot rest in a receptacle, and a pump that can be conveniently operated and is operative to force a solution from the container into the foot receptacle, so as to spray the foot thoroughly while the latter is supported on the foot rest.

To these and other ends, the invention consists 30 in the construction and arrangement of parts that will appear clearly from the following description when read in conjunction with the accompanying drawing, the novel features being pointed out in the claims following the specification.

In the drawing:

Fig. 1 is a plan view of a construction made in accordance with one practical embodiment of the invention;

Fig. 2 is an end elevation;

Fig. 3 is a vertical sectional view taken centrally of the device with parts appearing in elevation;

Fig. 4 is an enlarged sectional view on the line 4—4 of Fig. 1, and

Fig. 5 is a detail sectional view on the line 5—5 of Fig. 1.

In the construction shown, which is exemplary of one embodiment of the invention, there is 50 provided a low foot receptacle comprising a top wall 1, bottom wall 2, end walls 3, and likewise side walls, all preferably made of sheet metal. The foot receptacle has an opening 4 in its top wall 1, and 5 designates a protective bead extending around said opening 4 which may be in

the form of a rod welded to the adjacent edge of the metal top 1, as shown in Fig. 5.

The foot rest is preferably of inverted U-shaped cross-section, as indicated at 6, and is provided at the bottom with flanges 7 which are 5 welded or otherwise permanently attached to the bottom 2 of the receptacle, while 8 designates openings provided in the opposite walls of the foot rest in order to permit the horizontally directed liquid spray to pass therethrough for a 10 purpose that will appear hereinafter.

The supply of liquid is held in a container or tank that extends above the foot receptacle and is designated generally at 9, one end wall 3 of the foot receptacle constituting preferably also 15 one side wall of the liquid container, although the device may be otherwise constructed without changing its operation or effect. 10 designates a removable cap that is threaded on to a suitable collar surrounding a filling opening in 20 the top of the container whereby the latter may be charged with the necessary supply of liquid antiseptic.

Located in the liquid container and arranged vertically therein is a double-acting pump comprising a stationary outer housing 11 that rests upon the bottom of the container and is held in place by a strap 12 secured to the side wall. Located within the housing 11 is a tubular piston 13 provided with ports 14, ball valve 15, 30 and a gasket 16, while 17 designates a ball valve arranged in the valve support 18 in the housing 11. 19 is a pipe leading from the housing 16 near the top thereof to a spray nozzle 20 that extends through the wall 3 between the liquid 35 container and the foot receptacle and is provided with a small centrally disposed opening so as to direct a fine spray in a generally horizontal direction toward the zone immediately above the top of the foot rest, causing the liquid to be 40 thoroughly sprayed upon the foot while the latter is resting upon the top of the foot rest 6.

The hollow plunger 13 has a handle 21 located above the liquid container, and it will be understood that while the user places one foot on the 45 foot rest 6, he operates the plunger 21 upwardly and downwardly, causing a continuous spray through the nozzle 20. During the initial upward movement of the piston, liquid is drawn in through openings 22 and past the ball valve 17 50 into the housing 11 beneath the piston, and when the latter is next moved downwardly, the liquid passes the ball 15 and fills the interior of the piston 13 and of the housing above the gasket 16. On the next up-stroke, liquid is again drawn 55

in past the ball valve 17 and also forced out through pipe 19, and on successive downward and upward movements of the piston, liquid is forced out through openings 14 and through the pipe 19 to the spray nozzle.

Thus whenever the handle 21 is pulled upwardly and pushed downwardly, there is a continuous flow of liquid, resulting in an adequate spray that completely envelopes the foot on the foot rest in the receptacle. By providing the openings 8 in the opposite walls of the foot rest, the spray is prevented from impinging against the walls and forming a mist that would rise from the receptacle, but passes through the openings 8 and trickles down to the bottom of the receptacle. When the latter has collected a sufficient quantity of liquid in its bottom, the entire device can be turned over on end to empty the receptacle through the opening 4.

While the invention has been described with reference to the particular construction herein disclosed, it is not confined to the details set forth, and this application is intended to cover any modifications or adaptations of the improvements coming within the purposes thereof or the scope of the following claims.

I claim:

1. A portable foot spraying apparatus comprising a liquid container, a foot receptacle having an opening in its top wall, a foot rest in said receptacle having a convex foot engaging surface above the bottom and extending transversely of the receptacle to support a foot transversely

at its central portion, and means for forcing liquid from the container into the receptacle in a spray directed in a generally horizontal direction toward the zone just above said foot rest.

2. A portable foot spraying apparatus comprising a foot receptacle having an opening in its top wall, a foot rest in said receptacle having a convex foot engaging surface above the bottom and extending transversely of the receptacle to support a foot transversely at its central portion, a liquid container adjacent to said receptacle and extending thereabove, a pump arranged vertically in said liquid container and including a vertically movable piston, and liquid conducting means extending from said pump into said receptacle and acting to direct a spray of liquid into the receptacle in a generally horizontal direction toward the zone just above said foot rest.

3. A portable foot spraying apparatus comprising a liquid container, a foot receptacle having an opening in its top wall, foot spraying means located in said receptacle above the bottom comprising a convexly rounded foot engaging surface extending transversely of the receptacle and engageable with a foot transversely at its central portion so as to leave the toes of the foot free and in spread relationship, and means for forcing liquid from the container into the receptacle in a direction generally toward said foot supporting means.

FREDERICK B. EILERS.
